(57) **CLAIM**

The ornamental design for a break away rail car power connector nut, as shown and described.

DESCRIPTION

FIG. 1 is a perspective view of a break away rail car power connector nut, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a cross-sectional view thereof taken in the direction of line 8-8 shown in FIG. 2.

The broken line showings in FIGS. 1-8 are for the purpose of illustrating environmental structure and form no part of the claimed design.
